UNITED STATES PATENT OFFICE.

ROBERT E. CAMPBELL, OF WOODLAND, CALIFORNIA.

WASHING-MACHINE.

1,030,870.

Specification of Letters Patent.

Patented July 2, 1912.

Application filed June 20, 1910. Serial No. 567,794.

To all whom it may concern:

Be it known that I, ROBERT E. CAMPBELL, citizen of the United States, residing at Woodland, in the county of Yolo and State of California, have invented certain new and useful Improvements in Washing-Machines, of which the following is a specification.

My invention relates to an improvement 10 in washing machines of the particular style or kind upon which I obtained Letters Patent of the United States on the 24th day of September 1907, and numbered 866,912.

In the accompanying drawings, Figure 1 15 is a side elevation of the invention, and Fig. 2 is an end elevation thereof looking in from the left. Fig. 3 is a longitudinal sectional elevation taken on a line corresponding substantially to $z-z$, Fig. 2. Fig. 4 is 20 a side elevation of the mangle and pinion, and Fig. 5 is a cross section thereof on line $z-z$, Fig. 4.

The machine upon which this improvement is made is a hand machine and designed to be operated exclusively by hand 25 power, but it was found desirable for various reasons to convert the machine into a power machine so that it can be run without any expense or outlay of personal labor in 30 its operation and be connected up with any suitable source of power, such as a small water motor or electric motor or other power that may be available for the purpose.

The invention herein therefore resides essentially in the operating mechanism as it is connected up with the wash tank and other parts substantially as disclosed in my said patent and as will now appear.

Thus, referring to the said parts, F represents a metallic frame of substantially A 40 shape in side elevation as shown in this instance with the tank T pivoted off its middle portion or center of gravity at a to be off balance substantially as shown and so as to afford a considerable downward tilting and throw of the long end of the tank as compared with the short end and thus contribute to the tossing of the wash within the 45 tank for cleansing the same, it being understood that so far as the frame and the tank together are concerned with spring balancing mechanism there is no novelty claimed in this application.

The tension or balancing mechanism for the tank upon the frame consists in the

spiral spring S and the two sets of arms 2 and 3 respectively with which said spring is connected and which in turn are rigidly mounted on the bottom and center of the frame B which constitutes the immediate support of the tank upon the base frame F. The said link or links 2 are projected in a line of about forty five degrees to the bottom of the tank downward from the short end 60 of the tank back of its pivot a , while the link 3 is shorter and drops from the opposite side of said axis a and extends down to connect with the links 2 approximately near the point of connection of the spring S. 65 The effect and value of this arrangement is that by means of the spring the tank will be held normally in a horizontal position and the spring will operate to effect this restoration or position automatically. Therefore 70 the balancing of the tank upon the frame work or base is effected primarily by the said spring and the said links related as shown and no other mechanism is needed to assist in obtaining this result. 75

The other parts of the machine shown have to do with the operation or with the power for this purpose, the same, however, being arranged to coöperate with the said spring and link mechanism, and with the 80 peculiar mounting of the tank upon the frame, the whole therefore being of unitary plan and result and the operating mechanism necessarily being modified or peculiarly adapted to work with the other parts 85 90 in the manner shown and described.

Of course it will be understood that a machine of this kind to get effective results is necessarily limited in its tilting movement, the idea being that washing of the 95 clothing results from the tossing of the same with the water to and fro within the long tank and in which the wash is cleansed by the agitation in the presence of water under the right conditions of soap and heat.

Now, having in view this structure as above described, with everything ready to be power operated, I provide a segmental mangle or rack M supported from the short end of the tank by arms m pivoted upon the 100 bottom and short end of the tank and having the rack 7 or teeth therein adapted to be engaged between the sides of the mangle by a pinion 8 upon a power actuated shaft 10. A pulley, sheave or sprocket wheel, or 105 its equivalent, indicated by 12, is mounted upon this shaft and adapted to receive 110

power connections from any suitable source by belt or teeth. The said shaft may be provided with a fly-wheel if desirable or the wheel 12 itself may be of a weight and construction adapted to serve as a fly-wheel, such means being necessary with power to promote uniformity of movement or action in the tank and to assist the spring S in doing its work in tilting the tank as well as 5 overcoming dead centers in the mangle, it being understood that the said spring is adapted to contribute balancing effect to the tank in conjunction with the balance wheel in the operation. That is, when the long 10 end of the tank has tilted low, the spring is arranged to assist in bringing it back to its horizontal position and the links 2 and 3 are positioned in respect to the axis of the tank to promote this result. The shaft 10 having its connection with the mangle radially beneath the axis of tank pivot and the mangle being connected with the short end 15 of the tank brings about the desired co-operation between the spring and the mangle and gives harmony to all the movements and there is no strain or undue tension at any point.

Among the details of construction it is to be observed that the mangle or rack therein 20 has more teeth or rungs than there are teeth in the sprocket wheel or pinion, and of course the length of stroke is determined by the length of the rack in the mangle and the speed and size of the pinion along with 25 the speed of the driving motor, whatever it may be. However, the speed of the tank or number of tilts should not be over seventy per minute, and it may be something less than that with good results.

40 A wringer (not shown) can be placed as usual on the top of the body or tank immediately over the pivot thereof and within convenient reach for the operator from the short end of the tank and which will act as 45 a counterbalance in the operations of the machine as it swings from one side to the other of said pivot.

The machine is shown herein as having a 50 crank handle C applied to the shaft 10 for operating purposes, and the tank or body is tilted back and forth by the operation of the parts primarily controlled by said crank handle as is obvious. A handle portion 4 is shown as attached to the upper portion of 55 the tank for the purpose of hand operating the machine when desired.

The machine being pivoted entirely above the axle, renders it impossible to operate without the spring.

60 The coöperation of the mangle with the spring is, that when driven by power the swinging mangle or rack from the short end of the machine acts to fix the exact distance of swing downward of both ends of the 65 tank and makes the action uniform, because

the reverse always comes at the same places in the ends of the mangle, and the balance wheel helps to carry across said ends and equalize the travel both ways. The fly-wheel also assists in overcoming the inertia 70 of the shifting load in the tank. The spring S also enters into these calculations and is taken account of in providing a balance so that the two parts will work in harmony.

It will be observed that the mangle M 75 has a bowed spring 14, or its equivalent at its connection with the base frame of the tank T, and that the upper ends 15 of the two arms of the mangle are T shaped with notches in the top and ends of the cross bar 80 in which spring 14 is engaged at its ends. The said spring exerts a constant pressure, holding the swinging mangle to the pinion, accelerates the motion at the ends, prevents dead centers and reduces friction. Said 85 arms m are pivoted in projections 16 from the skeleton base frame B which carries the tank and is pivoted on frame F. I have tried many methods for power, but find the one adopted the only one that will take care 90 of the shifting load constantly going ahead with no pull or jerk back on gear when the load chucks in the end of the tank. In my machine the load is lifted and when it reaches the proper angle it moves rapidly 95 of its own weight and strikes the opposite end of the tank with great force. I then elevate the latter end and the load goes the other way. 20 represents a catch brace pivoted on frame F at its lower end and constructed to hook on a headed pin 21 on frame B and support the tank in horizontal position.

The belt N communicates power to the machine through fly wheel 12 in this instance.

What I claim is:

1. A washing machine having a clothes tank and a frame on which said tank is pivoted off its center lengthwise, a balancing 110 spring connected with the bottom of said receptacle at both sides of its pivot and with said frame at its other end and adapted to hold the receptacle normally in a horizontal position, in combination with a segmentally 115 shaped mangle pivotally suspended from the short end of said receptacle and extending forward beneath the same, a transverse shaft and a pinion thereon radially beneath the pivot of said receptacle, a fly-wheel on 120 said shaft and power connections therewith to operate the machine.

2. In washing machines, a supporting frame and a clothes tank pivoted thereon at its bottom off its center of gravity lengthwise and a spring mechanism to maintain the equilibrium of the tank comprising arms 125 engaged with the bottom of the tank at opposite sides of its pivot and projecting relatively toward the long end of the tank and 130

a spring connected with the said arms and fixed at the bottom of the supporting frame beneath the long end of the tank, in combination with a curved mangle pivoted at the 5 bottom of the short end of the tank and extending beneath the pivot of the tank on said frame and a rotatable pinion mounted radially beneath said pivot and in operating engagement with said mangle and adapted 10 to operate the tank through the mangle.

3. In washing machines, a supporting frame and a tank pivoted thereon off its center lengthwise and means to counter-balance the longer end of said tank and 15 hold the same normally in a substantially horizontal position comprising an arm fixed to the bottom of the short end of the tank at one side of its pivot and another arm

fixed to the tank on the other side of its pivot and the said arms united in substantially V shape, a balancing spring substantially in line with and in extension of the first named arm and engaged with the supporting frame at its other end, in combination with a power shaft beneath the pivot 25 of the said tank and a balance wheel thereon and a pinion and a segmental mangle engaged by said pinion and supported from the short end of the tank, substantially as set forth. 30

In testimony whereof I affix my signature in presence of two witnesses.

ROBERT E. CAMPBELL.
